OF MARION, INDIANA, A CORPORATION OF INDIANA.

SELECTING MECHANISM.

1,097,002.

Specification of Letters Patent.

Patented May 19, 1914.

Application filed December 19, 1910. Serial No. 598,265.

To all whom it may concern:

Be it known that I, ARTHUR E. CASE, a resident of Chicago, in the county of Cook and State of Illinois, have invented certain new and useful Improvements in Selecting Mechanism, of which the following is a full, clear, and exact description.

The invention relates to apparatus adapted to be used in connection with multi-party telephone-lines, for selectively connecting sub-stations to the line for speech-transmission, and the invention designs to provide improved apparatus for sending impulses over a multi-party line, to telephonically connect a selected station to the line, to lock out the remaining sub-stations from the line, and to signal or ring the selected sub-station.

The invention also designs to provide improved apparatus for this purpose whereby the exchange-operator can quickly cause the selecting, locking-in, locking-out and signaling operations for multi-station lines, to be effected.

The invention consists in the several novel features hereinafter set forth and more particularly defined by claim at the conclusion hereof.

In the drawings: Figure 1 is a diagrammatic view of a lock-out telephone system embodying the invention. Fig. 2 is a diagrammatic view of the sub-station apparatus connections adapted to be operated by the selective calling stepping-up apparatus at the exchange. Fig. 3 is an elevation of the selector-switch and associated parts. Fig. 4 is a section taken on line 4—4 of Fig. 3. Fig. 5 is a side elevation of the master-key. Fig. 6 is a section on line 6—6 of Fig. 5. Fig. 7 is a section taken on line 7—7 of Fig. 5.

The improved selecting and calling apparatus is adapted for use in connection with the operation of multi-party lines, in which each sub-station is usually equipped with an electro-magnetically operated stepping-up mechanism which serves to lock in one or two selected sub-stations on the line and to lock out all the rest, the device under the control of the exchange-operator operating the stepping-up mechanism automatically to lock in the selected station, to lock out all the rest and to signal the sub-station.

A sub-station equipment for which the selective mechanism is adapted, is diagram-

matically illustrated in Fig. 2 and comprises a polarized stepping-up electro-magnet a , an arm a' adapted to be operated in either direction from its centralized normal position by impulses of opposite polarity and a pawl a^6 carried by said arm for stepping up a ratchet a^7 when impulses of positive polarity are sent through magnet a . The ratchet a^7 carries a wiper-contact a^2 which is adapted to engage a switch-contact a^3 of a circuit which controls a locking-in magnet a^5 and said ratchet has a cam which is adapted to operate a group of switch contacts 90, 91 and 92 which control a ringing circuit at the sub-station. The locking-in magnet a^5 controls a group of switches 98, 99, a^8 , a^9 , a^{10} which control a circuit for speech-transmission. The wiper-contacts a^2 at the sub-stations respectively, are timed to successively engage contacts a^3 respectively so that by selectively sending an impulse of alternating current over a circuit in which said contacts are included, any sub-station on the multi-party line may be locked in or telephonically connected to the line. An impulse of negative polarity causes magnet a to operate arm a' in the opposite direction, to release a detent which holds ratchet a^7 and permits the ratchet to be restored to its normal position, by a retraction spring as well understood in the art. It will be understood that any desired number of sub-stations may be connected to a party-line, each station being provided with similar mechanism for controlling the sub-station connections with the line.

Each party-line comprises conductors b , b' extending between the exchange and the sub-stations. These conductors terminate in a spring-jack b^2 at the exchange and a suitable line-signal c is connected to the spring-jack, as well understood in the art.

The exchange is provided with a cord-loop, to which an answering-plug d , a calling-plug d' , a listening-key f , a ringing-key f' for the calling-line, and a ringing-key f^2 for the called line, of usual construction and arrangement, are connected in usual manner, as will be clear from Fig. 1 of the drawings.

A continuously operating make-and-break device G comprises an arm g^3 which is caused to vibrate continuously by a magnet g^4 which is included in a local circuit g^6 , and is controlled by a contact g^8 on arm g^3 and a sta-

tionary contact g^7 . When vibrator-arm g^3 is in position to close the local circuit g^5 , magnet g^4 will be energized to shift the vibrator-arm and break the local circuit, and this will cause the arm to be continuously vibrated. This continuously vibrating arm controls circuits for alternately transmitting impulses of opposite polarity over the telephone-line, by vibrating between a contact g 10 in a circuit for high potential of one polarity for sending stepping-up impulses over the line, and contact g^2 in a circuit for low potential of opposite polarity to the stepping-up impulse for sending impulses for removing residual magnetism and electrostatic charges from said circuit. Vibrator-arm g^3 also engages the contact g' which is included in a circuit for locking-in impulses when the said arm is out of contact with contact g .

20 An electro-magnet L is provided, to cause a circuit to be established over which impulses, caused by the device G , may be sent over the telephone-line and this magnet is included in a circuit controlled by the ring-keys of the cord-loop and controls a group of switch-contacts $l^1, l^2, l^3, l^4, l^5, l^6$. Contacts l^1, l^2 are normally in engagement and are included in a circuit over which an initial impulse is sent by the vibrator G and are separated when the magnet L is energized to interrupt this circuit, and contact l^2 is shifted into engagement with contact l^3 , so that current for causing electro-magnet L to remain energized will be directed to flow 30 through a resistance-coil l^7 . The winding of magnet L is connected by a conductor 15' to a conductor 15 which is connected to the positive side of battery i . Said winding is also connected by a conductor 16 to contact l^7 . A conductor 17 is connected to contact l^2 , resistance-coil l^7 and a contact 18 of a key k^1 . Contact l^5 is connected to the negative side of battery i , by conductor 61 and is normally in engagement with contact l^4 . 40 The latter is connected by a conductor 65 to the winding of an electro-magnet 67 for stepping up a selector-switch M , and when contact l^4 is shifted by energization of magnet L , it will engage contact l^6 which is connected by a conductor 55, to the vibrator-arm g^3 , to close a circuit for causing impulses to pass through the magnet of the selector-switch M . Magnet H is, for convenience, usually mounted on the frame m^7 which supports the selector-switch.

50 Selector-switch M is provided for causing an impulse of alternating current to pass over conductor b' of the line to the stepping-up relays at the sub-stations, to cause the selected station to be telephonically connected to the telephone-line. This selector-switch is operated by a polarized electro-magnet having windings 67 and an arm m , which is normally held in its central position by spring-pressed levers m^8 which are

55 pivoted to a suitable frame m^7 , as at m^8 and engage a stud m^9 on said arm. This arm m is operated in one direction from its centralized position, by current of one polarity (positive) passing through windings 67, to 70 shift a pawl m^{10} which steps up a ratchet-wheel m^{11} . A detent m^{12} holds the ratchet-wheel between the stepping-up movements of pawl m^{10} . Arm m is shifted in the opposite direction from its normal central position by current of opposite polarity (negative) passing through windings 67, to cause a stud m^9 to 75 strike the tail of detent m^{12} and disengage it from the ratchet to cause the tail of pawl m^{10} to be arrested by an abutment on the frame as shown in Fig. 3, to also disengage 80 said pawl from the ratchet. When said detent and pawl have been thus released, the ratchet will be restored to its normal position, by a spring m^{13} .

85 An arm m^3 is secured to rotate with ratchet m^{11} and carries a brush-contact m' adapted to successively engage a series of segment-contacts r' . These segment-contacts are electrically connected to contacts 71 of a corresponding series of keys k respectively, which are operated to determine which station on a line shall be connected to the line for speech-transmission and signaling. There is one of such segment-contacts r' and one key k for each sub-station on the line. Each contact 71 is connected to one of the segment-contacts r' by a conductor 74, and all of the contacts 72 of the series are connected by a common conductor 73 to 90 vibrator-contact g' , which is included in a circuit over which an impulse of alternating current will pass when brush-contact m' engages one of the segment-contacts r' and the contacts 71, 72 of the corresponding key k , are closed. These keys k are adapted to be held in depressed position by a common spring-pressed locking-member k^8 and any key, which is held in depressed position 95 thereby, will remain in depressed position to hold its switch closed until another key is depressed. Depression of any key will initially operate the locking-member to release a depressed key, and said member will, after releasing a depressed key, hold the key last depressed, by means of teeth k^{11} . All of the keys k are mounted in a suitable frame k^9 and a series of keys k^1, k^2, k^3 and k^4 are also mounted in this frame and are adapted 100 to be released when any of these keys or any of the keys of the series k are depressed.

105 Ratchet-wheel m^{11} carries an abutment m^5 which is adapted to engage a switch-contact 76 to cause the latter to engage a contact 75, to establish a circuit which causes the operation of a ringing-magnet O , to automatically establish a signaling or ringing circuit, whereby the selected sub-station on a multi-party line will be signaled after it has been telephonically connected to the line.

Electro-magnet O automatically controls a ringing-circuit for signaling the selected sub-station on the line, and comprises a winding 79 which is included in a circuit which is initially established by contacts 75, 76 and in a conductor 70 which is connected to battery-conductor 15 and to contact 75. Contact 76 is connected to the negative side of battery *i*, by a conductor 80 at such point that the potential of the circuit for operating the ringing-magnet O will be less (40 volts) than the stepping-up and releasing impulses sent over the line. To indicate to the exchange-operator, when the ringing circuit is operative, a signal-lamp *q* is included in a branch-conductor *q'* which is connected to conductor 70 in which the winding 79 of the ringing magnet is included.

Electro-magnet O controls a group of switches *o²*, *o³*, *o⁴*, *o⁵*, *o⁶*, *o⁷*, *o⁸*, *o⁹*, *o¹⁰*. Contacts *o²*, *o³* are normally engaged and are connected to the circuit for sending impulses over the line and are opened when the ringing magnet is energized after the stepping-up and selecting impulses have been sent over the line. Contact *o⁴* is connected to a contact 53 of a key *k'*, by a conductor 54 and contact *o²* is connected to vibrator-arm *g³*, by a conductor 55. Contacts *o⁴*, *o⁵* are normally engaged and contact *o⁴* is connected to a wire 61 which leads to the negative side of battery *i'*, and contact *o³* to a conductor 60 which is connected to the winding 67 of the magnet of the selector-switch and to contact 73. Contacts *o⁴*, *o⁵*, are included in the circuit for causing magnet L to remain operative to retain the circuits for transmitting impulses, complete. When magnet O is energized, contact *o³* is separated from contact *o⁴* to cause magnet L to become deenergized so that the switch-group controlled by magnet L, will be restored to normal position to render the impulse sending device inoperative to transmit impulses over the line. Contacts *o⁶*, *o⁷*, are normally open and when magnet O is energized, contact *o³* will cause said contacts to engage each other and be in contact therewith.

Contacts *o³*, *o⁶*, *o⁷*, when closed, will establish a circuit for automatically sending a releasing impulse of opposite polarity to that used for stepping up the selector-switch through windings 67. Contact *o⁵* is connected by conductors 15^b, 15^a, 15 to the positive side of the battery *i*, and contact *o³* is connected by conductor 60, to the winding 67.

Contact *o⁶* is connected by conductor 17 to the tip side of the line, and closes a circuit for current through holding-magnet H, when magnet O is energized. Said circuit will be as follows: battery *i*, conductors 15, 15^a, 15^b, contacts *o⁵*, *o⁶*, conductor 17, contacts 18, 19, conductor 20, contacts 21, 22, conductor 23, contacts 24, 25, conductor 26,

contacts 27, 28, conductors 29, 30, 31, contacts 32, 33, conductor 34, the tip of plug *d*, the tip spring of jack *b²*, line-conductor *b*, through all of the stepping-up coils on that line, conductor *b*, the sleeve-spring of jack *b²*, the sleeve of plug *d*, conductor 37, contacts 38, 39, conductors 40, 41, 42, contacts 43, 44, conductor 45, contacts 46, 47, conductor 48, contacts 49, 50, conductor 51, contacts 52, 53, conductor 54, contacts *o¹*, *o⁷*, conductor 80^a, the coil of magnet H, conductors 80 to the negative side of battery *i*.

Contact *o⁷* is connected to a conductor 80^a in which the winding of a holding-magnet H is included, and when magnet O is energized, contact *o⁷* will move into engagement with contact *o¹* to cause a circuit to be established through magnet H. Conductor 80^a is connected to conductor 80, which is connected to the negative side of the battery *i*, and when contact is broken at 75, 76 by release of the selector-switch, ringing magnet O will remain energized. Contacts *h²*, *h³*, which are operated by the holding-relay H, will be closed to complete a circuit for causing magnet O to remain operative to complete a ringing-circuit between contacts *o⁸*, *o⁷* and *o¹* which are connected to the ringing-circuit.

Key *k'* comprises contacts 52, 53, 18, 19 and connections for controlling a circuit whereby stepping-up impulses may be manually sent over the telephone-line by the exchange-operator. Key *k²* comprises contacts 49, 50, 21 and 22 and connections whereby alternating current may be manually sent over the line by the exchange-operator. Key *k³* comprises contacts 113, 46, 47, 24, 25, 112 and connections for manually controlling a circuit whereby a releasing impulse may be sent to all the sub-stations on the calling and called lines before the disconnection is made between the exchange and said lines. Key *k⁴* comprises contacts 43, 44, 27, 28 and connections whereby the exchange-operator can send generator current over a single party line. Contact 43 of key *k⁴* is connected to conductor 41 of the cord-loop, by a conductor 42, and contact 28 is connected to the other branch 30 of the cord-loop by a conductor 29.

The operation, in detail, of the system illustrated as an exemplification of the invention will be as follows: Any sub-station connected to the exchange by a multi-party line *b*, *b'* may signal the exchange-operator, by operating the magneto-generator located at such sub-station, which will cause generator current to pass over the metallic circuit of the line and operate the line-signal *c*, as well understood in the art. In response to this signal, the exchange-operator will insert an answering-plug *d* into the spring-jack *b²* of the line over which the signal is received, and will operate the lis-

tening key f to establish a circuit for speech-transmission between the operator's telephone set e and the calling sub-station, by means of the usual circuit connections and apparatus illustrated in the drawings and will ascertain the number of the calling sub-station and the number of the sub-station with which connection is desired. Thereupon, the exchange-operator will operate the selective-mechanism to cause impulses to be sent over the calling line to operate the stepping-up mechanism at all of the sub-stations and to telephonically connect the selected station to the line, and to lock out all others. In this operation the exchange-operator will first operate that key k corresponding in number to the calling sub-station, for example, "No. 6." Next, the exchange-operator will shift the ringing-key f' for the answering-plug d , which has been inserted into the spring-jack of the calling line. Thereupon, a circuit will be established for the operation of magnet L as soon as the vibrator-arm g^3 engages contact g^2 which is connected to battery i' , said circuit being as follows, viz.: battery i , conductors 15, 15', the winding of the magnet L , conductor 16, contacts l' , l^2 , conductor 17, switch-contacts 18, 19 of key k' , conductor 20, contacts 21, 22 of key k^2 , conductor 23, contacts 24, 25 of key k^3 , conductor 26, contacts 27, 28 of key k^4 , conductors 29, 30 and 31, contacts 32, 33 of ringing-key f' , conductor 34, the tip-contact of plug d , the tip-spring of spring-jack b^2 , line-conductor b' , all of the conductors 36 of the sub-stations on the line in which the stepping-up electromagnets a are included, line-conductor b , the sleeve-contact of the spring-jack b^2 , the sleeve of plug d , conductor 37, contacts 38, 39 of ringing-key f' , conductors 40, 41, 42, contacts 43, 44 of key k^4 , conductor 45, contacts 46, 47 of key k^5 , conductor 48, contacts 49, 50 of key k^2 , conductor 51, contacts 52, 53 of key k^5 , conductor 54, switch-contacts o' , o^2 of magnet O , conductor 55, vibrator-arm g^3 , contact g^2 , conductor 56 to battery i' . This impulse will be of the aggregate voltage of the batteries i (say 62 volts) and will be of such polarity as to cause all of the stepping-up polarized relays a at the sub-stations on the line to be energized so that their armatures will be operated to release the stepping-up mechanisms (if any are not in normal position) and insure their being in normal position at the commencement of each calling or stepping-up operation. This initial impulse of 62 volts energizes electro-magnet L and causes it to shift switch-member l^2 out of contact with switch-member l' and into contact with a switch-member l^3 , and also operates contact l^4 out of contact with member l^5 and into contact with a contact l^6 to establish circuit for causing impulses to be sent over the tele-

phone line and through the magnet of selector-switch M . The shifting of the switch-group controlled by electro-magnet L interrupts the circuit last described and causes a circuit to be established for holding this switch-group in shifted position, said circuit being as follows: battery i , conductors 15, 15', the winding of magnet L , conductor 16, resistance-coil l (2000 ohms), conductor 17, switch-members l^2 , l^3 , conductors 59, 60, contacts o^3 , o^4 of relay O , conductor 61 to battery i . Resultantly, the starting relay L will remain energized and will hold the group of switches controlled thereby in shifted position until the operation of the selector-switch has been completed and this current is interrupted at contact o^4 , o^3 by the operation of the ringing-relay O .

It will be observed that a starting impulse is impressed upon the line only when the vibrator-arm g^3 engages contact g^2 which controls the flow of potential from the low voltage battery i' , and before the stepping-up circuits become operative, so that an impulse of the aggregate voltage of batteries i' , i (say 62 volts) is impressed upon the circuit including the stepping-up relays a at the sub-stations when the starting-magnet L is actuated, and an important advantage of this arrangement and construction is that the circuit next to be described for the stepping-up operations will always be established when the vibrator is in one of its alternative positions and before the first stepping-up impulse is sent over the line, and that a releasing-impulse will be initially transmitted during each operation.

While the starting-magnet L remains operative and after the stepping-up relays a at the sub-stations have been restored to normal position by the initial impulse of 62 volts, a circuit for the transmission of stepping-up impulses through the relays a at all of the sub-stations on the line, will be established. Each time the vibrator-arm g^3 engages contact g , a stepping-up impulse (positive 50 volts) will be sent over the following circuit, viz.: battery i , conductors 15, 15', contact g , vibrator-arm g^3 , conductor 55, contacts o , o' , conductor 54, contacts 53, 52 of key k' , conductor 51, contacts 50, 49 of key k^2 , conductor 48, contacts 47, 46 of key k^3 , conductor 45, contacts 44, 43 of key k^4 , conductors 42, 41, 40, contacts 39, 38 of ringing-key f' , conductor 37, sleeve of plug d , sleeve-contact of spring-jack b^2 , line conductor b' , tip-contact of spring-jack b^2 , tip of plug d , conductor 34 of the cord-loop, contacts 33, 32, conductors 31, 30 and 29, contacts 28, 27 of key k^4 , conductor 26, contacts 25, 24 of key k^3 , conductor 23, contacts 22, 21

of key k^2 , conductor 20, contacts 19, 18 of key k' , conductor 17, contacts l^2 , l^3 , conductors 59, 60, contacts o^3 , o^4 and conductor 61 to the negative side of battery i . These impulses will be of that polarity and potential (50 volts) which will cause the polarized stepping-up relays a at the sub-stations to step up the brush-contacts operated thereby.

10 Synchronously, with the sending of stepping-up impulses over the line to the sub-stations, like impulses are sent over a circuit including the magnet of selector-switch M to step-up brush-contact m' in synchronism with the impulses to the stepping-up mechanisms at the sub-stations, so that a locking-in impulse, under control of the selector-switch will be transmitted to the selected station corresponding to the number 15 of the key K (No. 6) which has been operated. Said circuit will be as follows: battery i , conductors 15, 15 a , contact g , vibrator-arm g^3 , conductor 55, contacts l^6 , l^4 , conductor 65, the magnet-windings 67 of selector-switch M , conductor 60, contacts o^3 , o^4 , conductor 61, to battery i . These impulses are also controlled by vibrator-arm g^3 and therefore pass over said circuit in synchronism with the stepping-up impulses transmitted through the stepping-up relays a at the sub-stations on the line, and cause the selector-switch and sub-station relays a to be stepped up together.

10 Between each of the stepping-up impulses last described and every time vibrator-arm g^3 engages contact g^2 , an impulse of low potential (12 volts) and opposite polarity (negative) will be sent over the line to remove residual magnetism from the relays in the circuit and any electrostatic charge on the line, said circuit being as follows: battery i , conductor 56, contact g^2 , vibrator-arm g^3 , conductor 55, contacts o^2 , o' , thence over the line and same connections traversed by the stepping-up impulses, to conductor 17, contacts l^2 , l^3 , conductors 59, 60, contacts o^3 , o^4 and conductor 61 to battery i .

15 During the stepping-up operation of the selector-switch M , brush-contact m' will successively engage segment-contacts r' which are respectively connected to key-switches K , to control transmission of a locking-in impulse of alternating current over conductor b of the line to the selected sub-station (No. 6 corresponding to the key k that has been selected and operated by the exchange-operator) before the operator lets its ringing-key k' to start the calling and selecting mechanism. When the brush-contact m' contacts with any of the segment-contacts r' nothing occurs, except when it engages the segment which is connected to that key k which has been operated by the exchange-operator to close its contacts 71, 72.

20 Assuming "No. 6" key, series K , to have

been depressed, as is done when sub-station No. 6 is to be selected and signaled, an impulse of alternating current for causing that sub-station to be locked in, will be, when brush-contact m' engages the segment connected to said key k , sent over the following circuit, viz.: ground t' , generator t , conductor 69, arm m , brush-contact m' , that segment r' which is connected to the key k which has been operated, its conductor 74, 25 contacts 71, 72 of the depressed key k , conductor 73, vibrator-contact g' , arm g^3 , conductor 55, contacts o^2 , o' , conductor 54, contacts 53, 52 of key k' , conductor 51, contacts 50, 49 of key-switch k^2 , conductor 48, 30 contacts 47, 46 of key k^3 , conductor 45, contacts 44, 43 of key k^4 , conductors 42, 41, 40, contacts 39, 38 of ringing-key k' , conductor 37 of the cord-loop, the sleeve of plug d , sleeve-contact of spring-jack b^2 , line conductor b , conductor 36 at that sub-station (No. 6) at which the brush-contact a^2 is then engaging its contacts o^3 , conductor a^4 , locking-in magnet a^6 , conductor 100, to ground 101. This actuation of the magnet a^6 at the selected sub-station operates a group of switches which connects that sub-station to the line-conductors for speech transmission.

35 It will be understood that the contacts a^3 at the different sub-stations on the line are disposed to be successively engaged by their brush-contacts a^2 , so that only the selected station will be connected to the party-line b , b' by the locking-in impulse of alternating current determined by the exchange-operator when operating one of the keys k . The locking-in impulse is impressed upon the circuit while the vibrator-arm g^3 is out of contact with switch-member g and the locking-out impulses (50 volts) are transmitted, while the vibrator g^3 engages the contact g^2 from which 12 volt current is impressed upon the line, and resultantly all possibility of confusion of the stepping-up and locking-in impulses is overcome.

40 When impulses in sufficient number have been sent over the line to step up the relays a at the sub-stations and the selected station has been telephonically connected to the line and at the end of the sweep of brush-contact m' of the selector-switch M , a circuit will be established by abutment m^5 on the arm m^3 for signaling automatically the selected sub-station, to notify the sub-station if a call originates there that it has been locked in, or when the selecting apparatus has been operated over the line of a called station, to ring up that station. After brush-contact m' of the master-switch has been completed the transmission of locking-in impulses and has passed out of engagement with the last of the series of segment-contacts r' , abutments m^5 on arm m^3 will engage spring-contact 76 to shift it against 45

contact 75, whereupon the following circuit will be momentarily established, viz.: battery *i*, conductor 70 in which the winding 79 of electro-magnet O is included, contacts 5 75, 76, conductor 80 to battery *i*. This circuit will energize electro-magnet O to cause its armature to shift the associated group of switch-contacts and to hold them in shifted position as long as said circuit remains 10 closed, and to establish a ringing circuit. Thereupon, a circuit will be established through holding-magnet H which causes the current for magnet O to continue until the exchange-operator restores the ringing-key 15 *f'* to normal position, which will be as follows: battery *i*, conductor 70 (40 volts), conductors 15, 15^a, 15^b, contacts *o*⁵, *o*⁶, conductors 82, 17, contacts 18, 19 of key *k'*, conductor 20, contacts 21, 22 of key *k*², conductor 20 23, contacts 24, 25 of key *k*³, conductor 26, contacts 27, 28 of key *k*⁴, conductors 29, 30, 31, contacts 32, 33 of ringing-key *f'*, conductor 34, tip of plug *d*, tip-contact of spring-jack *b*², line-conductor *b'*, conductors 25 36 of all of the sub-stations, in which the stepping-up relays *a* are included, line-conductor *b*, the sleeve-contact of spring-jack *b*², sleeve of plug *d*, conductor 37 of the cord-loop, contacts 38, 39 of the ringing-key *f'*, 30 conductors 40, 41, 42, contacts 43, 44 of key *k*⁴, conductor 45, contacts 46, 47 of key *k*³, conductor 48, contacts 49, 50 of key *k*², conductor 51, contacts 52, 53 of key *k'*, conductor 54, contacts *o*⁷, *o*⁸, a conductor 80^a 35 (including the winding of holding-magnet H), conductor 80 to battery *i*. Current passing over this circuit is of insufficient voltage to actuate the magnets *a* at the sub-station, being less (40 volts) than the voltage necessary (50 volts) to operate said magnets, and furthermore the winding of the holding-relay H is of high resistance (say 3000 ohms) so that the operation of the sub-station magnets will be effectively prevented. The last 40 45 mentioned circuit will complete and maintain the following ringing or signaling circuit, viz.: ground *t'*; generator *t*, conductor 69, contacts *o*⁸, *o*⁷, *o*⁶, conductor 54, contacts 53, 52 of key *k'*, conductor 51, contacts 50, 50 49 of key *k*², conductor 53, contacts 47, 46 of key *k*³, conductor 45, contacts 44, 43, conductors 42, 41, 40, contacts 39, 38 of ringing-key *f'*, conductor 37 of the cord-loop, sleeve of plug *d*, sleeve-contact of spring-jack *b*², line-conductor *b*, conductor 36, conductor 89, contacts *a*¹⁰, *a*⁹ of the locking-in relay *a*⁵ of the selected sub-station, conductor 89^a, contacts 90, 91 which are then held in contact by the arm of the stepping-up mechanism, conductor 93, switch-hook contacts 94, 95, conductor 96 in which a bell 97 is included, contacts 98, 99 of the locking-in magnet *a*⁶, and conductor 100 to ground 101. In this manner, the ringer for signaling the selected station will be operated to

indicate to that station that the locking-out and locking-in operations have been completed, or when the calling mechanism is operated over a called line, the selected sub-station will be notified that communication therewith is desired and that a connection has been made therewith. 70

When the ringing-magnet O is operated as last described to automatically establish the signaling-circuit for the selected sub-station, 75 signal-lamp *q* is operated at the exchange to indicate to the exchange-operator, that the bell at the sub-station is ringing. When the ringing-magnet O is energized as hereinbefore described, the circuit through the starting magnet L will be interrupted at contacts *o*³, *o*⁴ which will cause the group of switches operated by the magnet L to be restored to their normal position and this restoration interrupts the circuit for the selector-switch M at contacts *l*⁴, *l*⁵ so that no further impulses will pass through the winding 67. Thereupon, a releasing or restoring impulse of opposite polarity to that used for selector-switch M, will be sent 80 through the winding 67 of relay *m* to cause its arm *m* to release the operating and holding pawls of the ratchet *m*⁶ by which the brush-arm *m*³ is stepped up and held. The circuit for causing this releasing impulse to 85 pass through helix 67 will be as follows, viz.: battery *i*, conductor 15, 15^a, contacts *o*⁶, *o*⁵, conductor 60, helix 67, conductor 65, contacts *l*⁴, *l*⁵, conductor 61 to battery *i*. The selector-switch will then be restored to 90 its normal position, in readiness for another operation. Next, the operator will restore ringing-key *f'* to normal position and the interruption of the circuit at the ringing-key will break the circuits in which the ringing-magnet O is included, which will interrupt the circuit for the holding-magnet H at contacts *h*², *h*³, whereupon said magnet O will be restored to normal position and the signal-lamp *q* will be extinguished. The 95 entire selecting and calling mechanism will then be in normal position with the exception of the key K (No. 6) which will be restored when the exchange-operator depresses key *k*³ to send a releasing impulse 100 over the line after the telephonic communication between the sub-stations has been completed, or when any of the keys K, *k*¹, *k*², *k*⁴ are next operated. 105

While the locking-in and locking-out operations are caused by the operation of the calling and selecting apparatus, at the exchange has been described in connection with a calling sub-station, it will be understood that the same operation results when this 110 apparatus is operated in connection with a called station when the companion-plug *d*' of the cord-loop is in the spring-jack of the called line and the ringing-key *f*² is operated in lieu of the ringing-key *f'* of the 115 120 125 130

same cord-loop. As soon as the exchange-operator has selected and signaled the called line by operation of the selecting and calling devices in like manner to that employed for locking in the calling sub-station, all of the sub-stations on the line over which the call is received, and on the line to which the called station is connected, will be locked out of the lines, except the calling sub-station and the called station, and circuit for speech-transmission will be completed as soon as the receiver is removed from the switch-hook at the called station, in manner well understood in the art.

When the conversation between the connected sub-stations has been completed and the usual disconnecting signal has been received by the exchange-operator, the latter will depress key k^3 to cause a releasing impulse to be sent to restore the stepping-up mechanisms on all of the stations of the called line and the calling lines, to normal position. For this purpose, the exchange-operator, in addition to operating key k^3 will operate the ringing keys f^2 , f' , whereupon an impulse for restoring the polarized relays at all of the sub-stations will be established over the following circuit, viz.: battery i , conductor 15, conductor 111, contacts 112, 25, conductor 26, contacts 27, 28 of key k^4 , conductors 29, 30, 31, contacts 32, 33, conductor 34, the tip contact of the spring-jack b^2 , line-conductor b' , conductors 36 of all of the sub-stations on the line and in which the stepping-up relays a are included, line-conductor b , sleeve-contact of the spring-jack b^2 , sleeve of plug d , conductor 37 of the cord-loop, contacts 38, 39, conductors 40, 41, 42, contacts 43, 44 of key k^4 , conductors 45, contacts 46, 113 of key k^3 , conductors 114, 61 to battery i . This impulse will be of such polarity as to operate the polarized magnets of the stepping-up relays a at the sub-station so as to cause the holding-pawls to release the ratchets and cause them to release the latches for the contacts operated by the locking-in relay of the connected sub-station and to restore the stepping-up mechanisms to their normal position. A like circuit through the ringing key f^2 causes the stepping-up relays of all of the sub-stations on the called line to be restored to their normal position. Thereupon, the entire equipment will be in its normal position in readiness for another operation. If two sub-stations on the same line are to be connected for speech-transmission, the operator will operate the corresponding keys K which will cause a locking-in impulse to be sent to each of said stations by the selector-switch.

In event the vibrator should become inoperative the exchange-operator can, when the ringing-key of the cord-loop has been shifted, send stepping-up impulses over the

lines, by depressing key k' and operating the ringing-key once for each stepping-up impulse. Contact 116 is connected to battery-conductor 15, to conduct current over the impulse circuit when the ringing-key is operated. By means of key k^2 , the exchange-operator may send alternating current to the selected station to lock it in, and said key is provided with a contact 117 which is connected to generator-wire 69. By means of key k^4 , the operator can send generator current over a single party line, being provided with a contact 118 which is connected to generator-wire 69.

The invention is not to be understood as restricted to the particular construction and organization set forth and may be modified within the scope of the appended claims without departing from the spirit and scope of the invention, and while the invention has been particularly described in connection with a multi-party telephone-system, it will be understood that certain features might be embodied in apparatus for selecting and signaling over other lines, to which a number of stations are connected and which are to be selected and signaled.

Having thus described the invention, what I claim as new and desire to secure by Letters Patent, is:

1. In a lock-out telephone system, the combination with switching devices at the sub-stations and a line of a circuit and means for alternately sending different impulses over the line, and electro-magnetically operated means for controlling the circuit to render it operative for the transmission of impulses.

2. In a lock-out telephone system, the combination with switching devices at the sub-stations and a line of a circuit and means for sending impulses over the line, electro-magnetically operated means for controlling the circuit to render it operative for the transmission of impulses, and means for selectively transmitting a different impulse over the line between the first mentioned impulses.

3. In a lock-out telephone system, the combination with switching devices at the sub-stations and a line of a circuit and means for alternately sending different impulses over the line, electro-magnetically operated means for controlling the circuit to render it operative for the transmission of impulses, and means for selectively transmitting a different impulse over the line.

4. In a lock-out telephone system, the combination with switching devices at the sub-stations and a line of a circuit and means for alternately sending different impulses over the line, electro-magnetically operated means for controlling the circuit to render it operative for the transmission of impulses, and means for automatically restoring the

controlling means after the impulses have been transmitted.

5. In a lock-out telephone system, the combination with switching devices at the sub-stations and a line of a circuit and means for sending impulses over the line, electro-magnetically operated means for controlling the circuit to render it operative for the transmission of impulses, means for selectively transmitting a different impulse over the line between the first mentioned impulses, and means for automatically restoring the controlling-means after the impulses have been transmitted.
- 10 6. In a lock-out telephone system, the combination with switching devices at the sub-stations and a line of a circuit and means for alternately sending different impulses over the line, electro-magnetically operated means for controlling the circuit to render it operative for the transmission of impulses, means for selectively transmitting a different impulse over the line, and means for automatically restoring the controlling-means after the impulses have been transmitted.

15 7. In a lock-out telephone system, the combination with switching devices at the sub-stations and a line of a circuit and means for alternately sending different impulses over the line, a switch for controlling the circuit to render it operative for the transmission of impulses, and an electro-magnet for operating the switch.

20 8. In a lock-out telephone system, the combination with switching devices at the sub-stations and a line of a circuit and means for sending impulses over the line, a switch for controlling the circuit to render it operative for the transmission of impulses, an electro-magnet for operating the switch, means for selectively transmitting a different impulse over the line, between the first mentioned impulses.

25 9. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, and means for selectively transmitting a different impulse over the line.

30 10. In a lock-out telephone system, the combination with switching devices at the sub-stations and a line of a circuit and means for sending impulses over the line, a switch for controlling said circuit, an electro-magnet for operating the switch to render the circuit operative for the transmission of impulses, and means for causing the switch to be automatically restored to render the circuit inoperative after the impulses have been transmitted.

11. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, and means for causing the switch to be automatically restored to render the circuit inoperative after the impulses have been transmitted.

15 12. In a lock-out telephone system, the combination with switching devices at the sub-stations and a line of a circuit and means for sending impulses over the line, a switch for controlling the circuit to render it operative for the transmission of impulses, an electro-magnet for operating the switch, means for selectively transmitting a different impulse over the line between the first-mentioned impulses, and means for automatically causing the switch to be restored to render the circuit inoperative after the impulses have been transmitted.

20 13. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, means for selectively transmitting a different impulse over the line, and means for causing the switch to be automatically restored to render the circuit inoperative after the impulses have been transmitted.

25 14. In a lock-out telephone system, the combination with switching devices at the sub-stations and a line of a circuit and means for alternately sending different impulses over the line, electro-magnetically operated means for controlling the circuit to render it operative for the transmission of impulses, and a key for controlling the operation of said electro-magnetically operated controlling-means.

30 15. In a lock-out telephone system, the combination with switching devices at the sub-stations and a line of a circuit and means for sending impulses over the line, electro-magnetically operated means for controlling the circuit to render it operative for the transmission of impulses, means for selectively transmitting a different impulse over the line between the first mentioned impulses, and a key for controlling the operation of said electro-magnetically operated controlling-means.

35 16. In a lock-out telephone system, the combination with switching devices at the sub-stations and a line of a circuit and means for alternately sending different impulses over the line, electro-magnetically operated means for controlling the circuit to render it operative for the transmission of impulses.

- render it operative for the transmission of impulses, means for selectively transmitting a different impulse over the line, and a key for controlling the operation of said electro-magnetically operated controlling-means.
17. In a lock-out telephone system, the combination with switching devices at the sub-stations and a line of a circuit and means for alternately transmitting different impulses over the line, electro-magnetically operated means for controlling the circuit to render it operative for the transmission of impulses, a key for controlling the operation of said electro-magnetically operated controlling-means, and means for automatically restoring the electro-magnetically operated controlling-means after the impulses have been transmitted.
18. In a lock-out telephone system, the combination with switching devices at the sub-stations and a line of a circuit and means for transmitting impulses over the line, electro-magnetically operated means for controlling the circuit to render it operative for the transmission of impulses, means for selectively transmitting a different impulse over the line between the first mentioned impulses, means for automatically restoring the electro-magnetically operated controlling-means after the impulses have been transmitted, and a key for controlling the operation of said electro-magnetically operated controlling-means.
19. In a lock-out telephone system, the combination with switching devices at the sub-stations and a line of a circuit and means for alternately sending different impulses over the line, electro-magnetically operated means for controlling the circuit to render it operative for the transmission of impulses, means for selectively transmitting a different impulse over the line, means for automatically restoring the controlling-means after the impulses have been transmitted, and a key for controlling the operation of said electro-magnetically operated controlling-means.
20. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, and a key for controlling the operation of said electro-magnet.
21. In a lock-out telephone system, the combination with switching devices at the sub-stations and a line of a circuit and means for sending impulses over the line, a switch for controlling the circuit to render it operative for the transmission of impulses, an electro-magnet for operating the switch, means for selectively transmitting a different impulse over the line between the first mentioned impulses, and a key for controlling the operation of said electro-magnetically operated controlling-means.
22. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, means for selectively transmitting a different impulse over the line, and a key for controlling the operation of said electro-magnet.
23. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, means for causing the switch to be automatically restored to render the circuit operative after the impulses have been transmitted, and a key for controlling the operation of said electro-magnetically operated controlling-means.
24. In a lock-out telephone system, the combination with switching devices at the sub-stations and a line of a circuit and means for sending impulses over the line, a switch for controlling the circuit to render it operative for the transmission of impulses, an electro-magnet for operating the switch, means for selectively transmitting a different impulse over the line between the first mentioned impulses, means for automatically causing the switch to be restored to render the circuit inoperative after the impulses have been transmitted.
25. In a lock-out telephone system, the combination with switching devices at the sub-stations and a line of a circuit and means for alternately sending different impulses over the line, a switch for controlling the circuit to render it operative for the transmission of impulses, an electro-magnet for operating the switch, means for selectively transmitting a different impulse over the line, means for causing the switch to be automatically restored to render the circuit inoperative after the impulses have been transmitted.
26. In a lock-out telephone system, the combination with switching devices at the sub-stations and a line of a circuit for transmitting impulses over the line, a continuously operating make-and-break device in said circuit, and electro-magnetically operated means for controlling the circuit to render it operative for the transmission of impulses.
27. In a lock-out telephone system, the combination with switching devices at the

sub-stations and a line of a circuit for transmitting impulses over the line, a continuously operating make-and-break device in said circuit for alternately causing different impulses to pass over the line, and electro-magnetically operated means for controlling the circuit to render it operative for the transmission of impulses.

28. In a lock-out telephone system, the combination with switching devices at the 10 sub-stations and a line of a circuit for transmitting impulses over the line, a continuously operating make-and-break device in said circuit, electro-magnetically operated 15 means for controlling the circuit to render it operative for the transmission of impulses, and means for selectively transmitting a different impulse over the line.

29. In a lock-out telephone system, the 20 combination with switching devices at the sub-stations and a line of a circuit for transmitting impulses over the line, a continuously operating make-and-break device in said circuit, for alternately causing different impulses to pass over the line, electro-magnetically operated means for controlling the 25 circuit to render it operative for the transmission of impulses over the line.

30. In a lock-out telephone system, the 30 combination with switching devices at the sub-stations and a line of a circuit for transmitting impulses over the line, a continuously operating make-and-break device in said circuit, electro-magnetically operated 35 means for controlling the circuit to render it operative for the transmission of impulses, and means for causing the controlling-means to render the circuit inoperative for the transmission of impulses.

31. In a lock-out telephone system, the 40 combination with switching devices at the sub-stations and a line of a circuit for transmitting impulses over the line, a continuously operating make-and-break device in said circuit, for alternately causing different impulses to pass over the line, electro-magnetically operated means for controlling the 45 circuit to render it operative for the transmission of impulses, and means for causing the controlling-means to render the circuit inoperative for the transmission of impulses.

32. In a lock-out telephone system, the 50 combination with switching devices at the sub-stations and a line of a circuit for transmitting impulses over the line, a continuously operating make-and-break device in said circuit, electro-magnetically operated 55 means for controlling the circuit to render it operative for the transmission of impulses, means for selectively transmitting a different impulse over the line, and means for causing the controlling-means to render the circuit inoperative for the transmission of impulses.

33. In a lock-out telephone system, the 60

combination with switching devices at the sub-stations and a line of a circuit for transmitting impulses over the line, a continuously operating make-and-break device in said circuit, for alternately causing different impulses to pass over the line, electro-magnetically operated means for controlling the circuit to render it operative for the transmission of impulses, means for selectively transmitting a different impulse over the line, and means for causing the controlling-means to render the circuit inoperative for the transmission of impulses.

34. In a lock-out telephone system, the combination with switching devices at the 70 sub-stations and a line of a circuit and a make-and-break device in said circuit, for alternately transmitting different impulses over the line, means for controlling said circuit to render it operative for transmission of the impulses, and means for causing said controlling-means to be actuated only when the impulse-device is in position to cause an impulse of one character to pass over the circuit.

35. In a lock-out telephone system, the combination with switching devices at the sub-stations and a line of a circuit and a make-and-break device in said circuit, for alternately transmitting different impulses 90 over the line, electro-magnetically operated means for controlling said circuit to render it operative for transmission of the impulses, and means for causing said magnet to be actuated only when the impulse-device 100 is in position to cause an impulse of one character to pass over the circuit.

36. In a lock-out telephone system, the combination with switching devices at the sub-stations and a line of a circuit and a make-and-break device in said circuit, for alternately transmitting different impulses over the line, electro-magnetically operated 105 means for controlling said circuit, means for causing said magnet to be actuated only 110 when the impulse-device is in position to cause an impulse of one character to pass over the circuit, and a key for controlling the operation of said electro-magnetically operated controlling-means.

37. In a lock-out telephone system, the combination with switching devices at the sub-stations and a line of a circuit and a make-and-break device in said circuit, for alternately sending different impulses over 120 the line, electro-magnetically operated means for controlling said circuit, means for causing said magnet to be actuated only when the impulse-device is in position to cause an impulse of one character to pass over the 125 circuit, and means for selectively transmitting a different impulse over the line.

38. In a lock-out telephone system, the combination with switching devices at the sub-stations and a line of a circuit and a 130

make-and-break device in said circuit, for alternately sending different impulses over the line, electro-magnetically operated means for controlling said circuit, means for causing said magnet to be actuated only when the impulse-device is in position to cause an impulse of one character to pass over the circuit, and means for automatically causing the electro-magnetically operated controlling-means to render the circuit inoperative for the transmission of impulses.

39. In a lock-out telephone system, the combination with switching devices at the sub-stations and a line of a circuit and a make-and-break device in said circuit, for alternately sending different impulses over the line, electro-magnetically operated means for controlling said circuit, means for causing said magnet to be actuated only when the impulse-device is in position to cause an impulse of one character to pass over the circuit, a key for controlling the operation of said electro-magnetically operated controlling-means, and means for automatically causing the electro-magnetically operated controlling-means to render the circuit inoperative for the transmission of impulses.

40. In a lock-out telephone system, the combination with switching devices at the sub-stations and a line of a circuit and a make-and-break device in said circuit, for alternately sending different impulses over the line, electro-magnetically operated means for controlling said circuit, means for causing said magnet to be actuated only when the impulse-device is in position to cause an impulse of one character to pass over the circuit, means for selectively transmitting a different impulse over the line, and means for automatically causing the electro-magnetically operated controlling means to render the circuit inoperative for the transmission of impulses.

41. In a lock-out telephone system, the combination with switching devices at the sub-stations and a line of a circuit and a make-and-break device for alternately sending different impulses over the line, a switch for controlling said circuit, an electro-magnet for operating said switch, a key for causing the magnet to be operated, and means for causing said magnet to be actuated only when the make-and-break device is in position to cause an impulse of one character to pass over the line.

42. In a lock-out telephone system, the combination with switching devices at the sub-stations and a line of a circuit and means for alternately transmitting impulses of different polarity over the line, and means for initially transmitting a restoring impulse of greater potential over the line.

43. In a lock-out telephone system, the combination with switching devices at the sub-stations and a line of a circuit and

means for alternately transmitting impulses of different polarity and potential over the line, a switch for controlling said circuit, an electro-magnet for operating said switch, a key for controlling the operation of said magnet, and means for transmitting an impulse of greater potential through said magnet and over the line.

44. In a lock-out telephone system, the combination with switching devices at the sub-stations and a line of a circuit and means for alternately transmitting impulses of high potential of one polarity, and impulses of opposite polarity and low potential, over the line, means for initially causing an impulse of the aggregate potential of the alternating impulses to pass over the telephone-line, and means for controlling the operation of said circuit.

45. In a lock-out telephone system, the combination with switching devices at the sub-stations and a line of a series of contacts for controlling transmission of locking-in impulses, a switch for successively engaging said contacts to selectively cause an impulse to be sent over the line, an electro-magnet for operating said switch, means for alternately sending different impulses over the line, and means for transmitting impulses of one character to said magnet to step up said switch.

46. In a lock-out telephone system, the combination with switching devices at the sub-stations and a line of a series of contacts for controlling transmission of locking-in impulses, a switch for successively engaging said contacts to selectively cause an impulse to be sent over the line, an electro-magnet for operating said switch, means for alternately sending different impulses over the line, means for alternately transmitting like impulses to said magnet, and a series of key-switches respectively connected to said contacts for selectively controlling the transmission of impulses by the electro-magnetically operated switch.

47. In a lock-out telephone system, the combination with switching devices at the sub-stations and a line of a selector-switch, an electro-magnet for stepping up said switch, means for synchronously causing impulses to be sent over the line and to said magnet to step up said switch, and means for selectively controlling the transmission of an impulse over the line by the selector-switch, and means for automatically establishing a signaling circuit after the selector-switch has been stepped up.

48. In a lock-out telephone system, the combination with switching devices at the sub-stations and a line of a series of contacts for controlling transmission of locking-in impulses over the line, an electro-magnetically operated switch for successively engaging said contacts, means for selectively

controlling the transmission of impulses by the operation of said switch on said contacts, and means for automatically establishing a signaling circuit after the selector-switch has been stepped up.

5. 49. In a lock-out telephone system, the combination with switching devices at the sub-stations and a line of a series of contacts for controlling the transmission of locking-in impulses over the line, a switch for successively engaging said contacts for selectively sending an impulse over the line, an electro-magnet for operating said switch, means for synchronously sending impulses 10 through said magnet and over the line, and means for automatically establishing a signaling-circuit after the selector-switch has been stepped up.

50. In a lock-out telephone system, the 20 combination with switching devices at the sub-stations and a line of a selector-switch, an electro-magnet for stepping-up said switch, means for alternately transmitting different impulses over the line, means for 25 sending impulses of one character to said magnet to step up the switch, and means for automatically establishing a signaling-circuit after the selector-switch has been stepped up.

30 51. In a lock-out telephone system, the combination with switching devices at the sub-stations and a line of a selector-switch, an electro-magnet for stepping-up said switch, means for alternately transmitting 35 different impulses over the line, means for sending impulses of one character to said magnet to step up the switch, means for selectively controlling the transmission of an impulse over the line by the selector-switch, and means for automatically establishing a signaling 40 circuit after the selector-switch has been stepped up.

52. In a lock-out telephone system, the combination with switching devices at the 45 sub-stations and a line of a selector-switch, an electro-magnet for stepping up said switch, means for alternately transmitting different impulses over the line, means for sending impulses to said magnet, keys for 50 selectively controlling the transmission of impulses by the switch, and means for automatically establishing a signaling circuit after the selector-switch has been stepped up.

53. In a lock-out telephone system, the 55 combination with switching devices at the substations and a line of a series of contacts for controlling transmission of locking-in impulses, a switch for successively engaging said contacts to selectively cause an impulse 60 to be sent over the line, an electro-magnet for operating said switch, means for alternately sending different impulses over the line, means for transmitting impulses of one character to said magnet to step up said 65 switch, and means for automatically estab-

lishing a signaling circuit after the selector-switch has been stepped up.

54. In a lock-out telephone system, the combination with switching devices at the sub-stations and a line of a series of contacts 70 for controlling transmission of locking-in impulses, a switch for successively engaging said contacts to selectively cause an impulse to be sent over the line, an electro-magnet for operating said switch, means for alternately sending different impulses over the line, means for transmitting impulses of one character to said magnet to step up said switch, a series of key-switches respectively connected to said contacts for selectively 75 controlling the transmission of impulses by the switch, and means for establishing a signaling circuit after the selector switch has 80 been stepped up.

55. In a lock-out telephone system, the 85 combination with switching devices at the sub-stations and a line of a selector-switch, an electro-magnet for stepping-up said switch, means for synchronously sending impulses to said magnet to step-up the switch, 90 and over the line, and means for automatically sending ringing current over the line after the impulses have been sent over the line.

56. In a lock-out telephone system, the 95 combination with switching devices at the sub-stations and a line of a selector-switch, an electro-magnet for stepping up said switch, means for synchronously sending impulses over the line and to said magnet to 100 step up said switch, means for selectively controlling the transmission of an impulse over the line by the selector-switch, and means for automatically sending signaling current over the line when said switch has 105 been stepped up by said impulses.

57. In a lock-out telephone system, the combination with switching devices at the sub-stations and a line of a selector-switch, an electro-magnet for stepping up said 110 switch, means for alternately transmitting different impulses over the line, means for sending impulses of one character to said magnet to step up the switch, and means for automatically sending signaling current 115 over the line when said switch has been stepped up by said impulses.

58. In a lock-out telephone system, the combination with switching devices at the sub-stations and a line of a selector-switch, an electro-magnet for stepping up said 120 switch, means for alternately transmitting different impulses over the line, means for sending impulses of one character to said magnet to step up the switch, means for 125 automatically sending signaling current over the line when said switch has been stepped up, and means for rendering the impulse-sending means inoperative when ringing current is sent over the line.

59. In a lock-out telephone system, the combination with switching devices at the sub-stations and a line of a selector-switch, an electro-magnet for stepping up said switch, means for alternately transmitting different impulses over the line, means for sending impulses of one character to said magnet to step up the switch, means for selectively controlling the transmission of an impulse over the line by the selector-switch, and means for automatically sending signaling current over the line when said switch has been stepped up. 70
60. In a lock-out telephone system, the combination with switching devices at the sub-stations and a line of a selector-switch, an electro-magnet for stepping up said switch, means for alternately transmitting different impulses over the line, means for sending impulses of one character to said magnet to step up the switch, means for selectively controlling the transmission of an impulse over the line by the selector-switch, and means for automatically sending signaling current over the line when said switch has been stepped up, and means for rendering the impulse-sending means inoperative when ringing current is sent over the line. 75
61. In a lock-out telephone system, the combination with switching devices at the sub-stations and a line of a selector-switch, an electro-magnet for stepping up said switch, means for synchronously sending impulses to said magnet to step-up the switch and over the line, electro-magnetically operated means for controlling the operation of the impulse-sending means, and means for automatically rendering the impulse-sending means inoperative after each stepping-up operation has been completed. 80
62. In a lock-out telephone system, the combination with switching devices at the sub-stations and a line of a selector-switch, an electro-magnet for stepping up said switch, means for alternately transmitting different impulses over the line, means for sending impulses of one character to said magnet to step up the switch, and electro-magnetically operated means for controlling the operation of the impulse-sending means. 85
63. In a lock-out telephone system, the combination with switching devices at the sub-stations and a line of a selector-switch, an electro-magnet for stepping up said switch, means for alternately transmitting different impulses over the line, means for sending impulses of one character to said magnet to step up the switch, electro-magnetically operated means for controlling the operation of the impulse-sending means, and means for automatically rendering the impulse-sending means inoperative after each stepping-up operation has been completed. 90
64. In a lock-out telephone system, the combination with switching devices at the sub-stations and a line of a selector-switch, an electro-magnet for stepping up said switch, means for alternately transmitting different impulses over the line, means for sending impulses of one character to said magnet to step up the switch, means for selectively controlling the transmission of an impulse over the line by the selector-switch, and means for automatically sending signaling current over the line when said switch has been stepped up. 95
65. In a lock-out telephone system, the combination with switching devices at the sub-stations and a line of a circuit and means for sending impulses over the line, a selector-switch and continuously operated electro-magnetically operated means for making and breaking the circuit for the transmission of impulses over the telephone-line. 100
66. In a lock-out telephone system, the combination with switching devices at the sub-stations and a line of a circuit and means for alternately sending different impulses over the line, a selector-switch and continuously operated electro-magnetically operated means for making and breaking the circuit for the transmission of impulses over the line. 105
67. In a lock-out telephone system, the combination with switching devices at the sub-stations and a line of a circuit and means for alternately sending different impulses over the line, and electro-magnetically operated means for making and breaking the circuit to cause different impulses to pass alternately over the line. 110
68. In a lock-out telephone system, the combination with switching devices at the sub-stations and a line of a circuit and means for sending impulses over the line, and a continuously operating vibrator for making and breaking the circuit to cause impulses to pass over the line. 115
69. In a lock-out telephone system, the combination with switching devices at the sub-stations and a line of a circuit and means for sending impulses over the line, a continuously operating vibrator for making and breaking the circuit to cause impulses to pass over the line, and means for controlling the circuit to cause a predetermined number of impulses to be sent over the line. 120
70. In a lock-out telephone system, the combination with switching devices at the sub-stations and a line of a circuit and means for alternately sending different impulses over the line, and a continuously operating electro-magnetically operated vibrator for making and breaking the circuit to cause different impulses to pass alternately over the line. 125
71. In a lock-out telephone system, the combination with switching devices at the sub-stations and a line of a circuit and means for alternately sending different impulses 130

over the line, a continuously operating electro-magnetically operated vibrator for making and breaking the circuit to cause different impulses to pass alternately over the line, and means for controlling the circuit to cause a predetermined number of impulses to be sent over the line.

72. In a lock-out telephone system, the combination with switching devices at the sub-stations and a line of a selector-switch, an electro-magnet for stepping up said switch, means for synchronously sending impulses to said magnet to step up the switch and over the line, means for initially sending a restoring impulse over the line, and electro-magnetically operated controlling means for the circuit over which the impulses are transmitted.

73. In a lock-out telephone system, the combination with switching devices at the sub-stations and a line of a circuit and means for sending impulses over the line and continuously operating electro-magnetically operated means for making and breaking a circuit for the transmission of impulses over the line, and electro-magnetically operated controlling means for the circuit over which the impulses are transmitted.

74. In a lock-out telephone system, the combination with switching devices at the sub-stations and a line of a circuit and means for alternately sending different impulses over the line, electro-magnetically operated means for making and breaking the circuit to cause different impulses to pass alternately over the line, and electro-magnetically operated controlling means for the circuit over which the impulses are transmitted.

75. In a lock-out telephone system, the combination with switching devices at the sub-stations and a line of a circuit and means for alternately sending different impulses over the line, a continuously operating electro-magnetically operated vibrator for making and breaking the circuit to cause different impulses to pass alternately over the line, and electro-magnetically operated controlling means for the circuit over which the impulses are transmitted.

76. In a lock-out telephone system, the combination with switching devices at the sub-stations and a line of a circuit and means for sending impulses over the line and continuously operating electro-magnetically operated means for making and breaking a circuit for the transmission of impulses over the line, and an electro-magnetically operated selector-switch operated by impulses of one character.

77. In a lock-out telephone system, the combination with switching devices at the sub-stations and a line of circuit and means for alternately sending different impulses over the line, electro-magnetically operated means for making and breaking the circuit

to cause different impulses to pass alternately over the line, and an electro-magnetically operated selector-switch operated by impulses of one character.

78. In a lock-out telephone system, the combination with switching devices at the sub-stations and a line of a circuit and means for sending impulses over the line, a continuously operating vibrator for making and breaking the circuit to cause impulses to pass over the line, and an electro-magnetically operated selector-switch operated by impulses of one character.

79. In a lock-out telephone system, the combination with switching devices at the sub-stations and a line of a circuit and means for alternately sending different impulses over the line, a continuously operating electro-magnetically operated vibrator for making and breaking the circuit to cause different impulses to pass alternately over the line, and electro-magnetically operated selector-switch operated by impulses of one character.

80. In a lock-out telephone system, the combination with switching devices at the sub-stations and a line of a circuit and means for sending impulses over the line, a selector-switch, and means for establishing a ringing circuit after a predetermined number of impulses have been transmitted, comprising an electro-magnet, and a switch operated thereby said means for establishing the ringing circuit being rendered operative by the selector switch, and located at the exchange.

81. In a lock-out telephone system, the combination with switching devices at the sub-stations and a line of a circuit and means for sending impulses over the line, a selector-switch, means for establishing a ringing circuit after a predetermined number of impulses have been transmitted, comprising an electro-magnet, and a switch operated thereby, and a ringing-key connected to render the ringing circuit inoperative said means for establishing the ringing circuit being rendered operative by the selector switch, and located at the exchange.

82. In a lock-out telephone system, the combination with switching devices at the sub-stations and a line of a circuit and means for sending impulses over the line, a selector-switch, and means for establishing a ringing circuit after the impulses have been transmitted, comprising an electro-magnet and a switch operated thereby, and an electro-magnet for maintaining the ringing circuit operative.

83. In a lock-out telephone system, the combination with switching devices at the sub-stations and a line of a circuit and means for sending impulses over the line, a selector-switch, means for establishing a ringing circuit after the impulses have been transmitted, comprising an electro-magnet and a

switch operated thereby, an electro-magnet for maintaining the ringing circuit operative, and a ringing-key connected to render the ringing current inoperative.

5 84. In a lock-out telephone system, the combination with switching devices at the sub-station and a line of a circuit and means for sending impulses over the line, a selector-switch, means for automatically establishing a ringing-circuit when a predetermined number of impulses have been transmitted, comprising an electro-magnet and a switch operated thereby, and an electro-magnetically operated controlling means for the 10 circuit over which impulses are sent, connected to the last mentioned switch and rendered inoperative when the ringing circuit is established.

85. In a lock-out telephone system, the combination with switching devices at the sub-stations and a line of a circuit and means for sending impulses over the line, electro-magnetically operated controlling-means for

said circuit, means for automatically establishing a signaling-circuit when a predetermined number of impulses have been sent over the line, and means for restoring said controlling-means when said ringing-circuit is rendered operative.

25

86. In a lock-out telephone system, the combination with switching devices at the sub-stations and a line of a circuit and means for sending impulses over the line, electro-magnetically operated controlling-means for said circuit, means for selectively sending an impulse over the line, means for automatically establishing a signaling-circuit when a predetermined number of impulses have been sent over the line, and means for restoring said controlling-means when said 40 ringing circuit is rendered operative.
